Filed July 5, 1960, Ser. No. 61,235

Term of patent 14 years

(Cl. D33—7)

FIGURE 1 is a front perspective view of a credenza table or similar article, showing our new design;

FIGURE 2 is a rear perspective view thereof; and

FIGURE 3 is a fragmentary perspective view of the leg structure.

The dominant features of the design reside in the portions shown in full lines in the drawing and are characterized by legs of angular cross section which are recessed into the inner side walls of the pedestals and spaced from the adjacent ends thereof, in combination with the framed panels on the front and rear faces of the pedestals, substantially as shown.

The side of the credenza not disclosed is substantially plain while the undisclosed inner pedestal face is the same in appearance as the pedestal face shown.

We claim:

The ornamental design for a credenza table or similar articles, substantially as shown and described.
